R. P. AKINS.
VIBRATING SCREEN.
APPLICATION FILED AUG. 31, 1914.

1,160,812.

Patented Nov. 16, 1915.

UNITED STATES PATENT OFFICE.

RANDALL P. AKINS, OF DENVER, COLORADO, ASSIGNOR TO COLORADO IRON WORKS COMPANY, OF DENVER, COLORADO, A CORPORATION OF MAINE.

VIBRATING SCREEN.

1,160,812.

Specification of Letters Patent. Patented Nov. 16, 1915.

Application filed August 31, 1914. Serial No. 359,490.

To all whom it may concern:

Be it known that I, RANDALL P. AKINS, citizen of the United States, residing at Denver, Colorado, have invented certain new and useful Improvements in Vibrating Screens, of which the following is a specification.

The present invention relates to improvements in vibrating screen mechanism adapted for use in sizing and classifying pulverized ore and other material where the necessity for a classifying, grading, or screening function exists.

The invention relates more particularly to that class of vibrating screens which are supported in an inclined position and are adapted to vibrate in a direction approximately at right angles to the plane of the screen surface. Screens of this general type are shown in United States Patents Nos. 738,435, dated September 8, 1903 and 814,952, dated March 13, 1906. In the former of these patents a screen is provided which is spring-supported and is freely poised or floated throughout its entire extent so as to vibrate as an entirety. Screens of this type however, being inclined, have a tendency to tilt forward, due to the combined weight of the vibrating parts and the load of material passing over the screen, with the result that they assume a greater degree of inclination than is desired. This brings the upper end of the screen against the stops for limiting its vibration, and all, or nearly all the vibration takes place at the lower end, the upper end thereby losing a large part of its efficiency. In order to obviate this tendency of the screen to rock longitudinally about the point of spring support and yet at the same time obtain practically all the advantages of the freely poised screen of the earlier patent, the screen disclosed in Patent 814,952 was provided with tie bars supported at one end to a stationary frame and at the other coupled to the spring members. The tie bars, experience has shown, tend to minimize the rocking tendency, but do not satisfactorily overcome the tendency of the screen to tilt forward. That is, if the position and stiffness of the tie bars compensates for the tilting tendency under certain conditions of load.

ing, they will not do so if the load of material passing over the screen is increased or diminished.

The present invention has for its object to provide for screens of this type an arrangement which will combine the advantages of both these forms and will give a more satisfactory and efficient device. This is done by providing adjustable attachment means for the fixed points of the spring, so that although this part of the spring is stationary when the machine is in operation, it is not immovably fixed but is susceptible of adjustment. The means referred to consists of any arrangement of elements to be placed between the lower spring member and the spring supporting bracket, whereby the spring can be placed and held in such a position as will counteract the tilting tendency alluded to.

With these and other objects in view the invention consists in the combination and arrangement of parts more fully set forth in the following specification, illustrated in the accompanying drawings and pointed out in the appended claims.

In the drawings, three forms are shown by way of example, it being understood that I do not limit myself to the specific constructions here illustrated but wish to avail myself of all modifications which will fall properly within the scope of the invention.

Referring to the drawings: Figure 1 is a side elevation, illustrating one embodiment of the present invention. Fig. 2 is a section taken on the line 2—2 of Fig. 1. Fig. 3 is a fragmental detail of a modified form of the invention. Fig. 4 is a fragmental detail of a further modification.

Referring to the drawings 1 designates a suitable upright framework, to which is secured by bolts 2 a stationary frame 3, on which is journaled a shaft 4, to which is secured a pair of multiple cam-wheels 5, arranged to act on parallel bars 6, connected by transverse bars 7 forming the body of the screen frame. The mesh material 8 of the screen is secured to suitable bars 9 and 10. To the upper surface of the frame bars 6 are attached contact plates 11, which are acted upon by the multiple cam wheels. To the lower surface of the bars 6 of the

screen-frame are attached double bow springs 13, located on opposite sides and composed of upper and lower members bows 14 and 15, connected at their extremities as shown at 16. The upper members of these springs are secured to the bars 6 by bolts 17 while the lower members are similarly secured by bolts 18 to a plate 20. A bracket 21 rigidly secured to the stationary frame 3, 10 is provided with a depending arm 22 to which a second plate 23, similar in size and shape to plate 20, is integrally formed. The lower bracket plate 23 has a centrally located boss or sleeve 23^a formed with a screw 15 threaded bore in which a screw 24 passes upwardly. The plate 20 to which the spring member 15 is bolted is provided with a centrally located recess 15^a. The plate 20 is supported by the screw 24 the upper end of 20 which has a bearing in the pocket or recess 15^a. A pair of adjusting screw bolts 25 are provided, one on either side of the supporting bolt 24. These bolts pass through perforations in the upper plate 20 and similar 25 ones in the lower plate 23. Two adjusting nuts 25^a are threaded on the stems of each of the bolts 25 and arranged one on either side of the plate 23.

Secured to the side bars of the stationary frame 3 are brackets 26 which are provided with inwardly projecting arms 27, occupying positions directly above the bars 6 of the screen frame. There are two of these brackets 26 on each side of the screen frame. In 35 these brackets are screws 28, whose lower extremities are engaged by the bars 6 of the screen frame and form stops to limit the upward movement of the screen frame when the latter is released by the cam-faces of the 40 multiple cam wheels 5. As the upward or reverse movement of the screen frame is suddenly checked by the stop screws 28, which are four in number as heretofore explained, the resulting sudden impact performs an important function in the screening of the material, as will be readily understood. Attention is called to the fact that by having the multiple cam-wheels centrally located with reference to the bars 6 of the screen 45 frame a uniform vibrating movement is obtained.

The supporting screw 24 can be adjusted vertically in relation to the plate 23 to thus vary the tension of the supporting spring 55 13. By loosening or tightening the other of the adjusting bolts 25 the angle of inclination of the spring support can be adjusted about its central and substantially vertical axis, or in other words, about its pivotal bearing on the upper end of the screw 24. By varying this adjustment to suit the needs of the differently weighted loads passing over the screen frame 6 the proper angle for the latter can be obtained which will obviate any tendency on the part of the screen

to tilt forward. This construction permits of a sensitive adjustment of the supporting spring about its vertical axis and at the same time does not entail the use of guides or other structural features, which would preclude the screen frames being freely poised or floated. 70

Fig. 3 illustrates a modified form of the application of the same principle. In this construction the lower plate 23 is dispensed with and the bracket end is formed with an interiorly threaded boss 23^b through which the supporting screw 24 is threaded. This upper plate 20' to which the lower spring member 15 is riveted, is made of inverted U-shape with two depending arms 20^a and 20^b equidistantly spaced from the screw 24. Adjusting screws 25' pass through inwardly threaded bosses 25^a located near the lower ends of said arms. Lock nuts 25^b are provided on the screws 25'. The inner end of each screw bears against the outer surface of the boss 23^b. By alternately loosening and tightening the adjusting screw bolts 25' exactly the same effect is produced as was accomplished in the form illustrated in Fig. 1. 85

A still further modification is shown by way of example in Fig. 4. In this form only one adjusting screw bolt 25^c is provided and this is rigidly carried by the boss 23^b and projects therefrom at right angles thereto. The plate 20^c has only one depending arm which extends downwardly at one side of and parallel to the bolt 24 and is perforated to receive the end of the adjusting bolt 25^c. This bolt is provided with two locking nuts 25^c. 95

The three forms illustrated all accomplish the same results and many others may be devised. 100

Having described my invention what I claim is:

1. In combination an inclined screen, stop means for limiting the upward movement of said screen, means for moving the screen downwardly in a direction transverse to its plane, spring means sustaining the screen and for forcing the screen upwardly to abut against the stops, and means for adjusting the spring means to alter the resistance of the spring means relatively in respect to the upper and lower ends of the screen to thereby compensate for the tendency of the screen to tip out of its proper inclined position due to the weight of the material passing over it, substantially as described. 110

2. In combination an inclined screen, cam means for giving successive downward movements to the screen in a direction transverse to its plane, stops at the upper and lower ends of the screen for limiting its upward movement, and spring means for giving the screen its upward movement in a direction transverse to its plane, and means for 115 120 130

adjusting the spring means to vary the force of the upward thrust of the screen at its lower end in respect to that at its upper end.

3. In combination an inclined screen, means for giving successive downward movements to the screen in a direction transverse to its plane, a spring of double bow shape for giving the screen its upward movement, the upper member of said spring being centrally connected with the screen about centrally thereof, means connected with the center of the lower bow of said spring for supporting the same, and means for canting said spring in relation to its support to compensate for the tendency of the screen to tip out of its proper inclined position due to its load, substantially as described.

4. In combination an inclined screen, means for giving successive downward movements to the screen in a direction transverse to its plane, a spring of double bow shape, the upper member of which is connected with the screen about centrally thereof, means connected with the center of the lower leaf or bow of the said spring for supporting the same, stop means at the upper and lower portions of the screen against which said screen is forced by the spring, and means for canting said spring in relation to its support and to the plane of the

stops to compensate for the tendency of the screen to tip out of proper inclined position due to its load, substantially as described.

5. In combination an inclined screen, means for giving successive downward movements to the screen in a direction transverse to its plane, a spring of double bow shape having its upper member centrally connected with the screen about centrally thereof, a bearing upon which the lower member of the spring bears pivotally at about its center, and adjusting means for canting said spring on said pivot bearing, substantially as described.

6. In combination an inclined screen, means for giving the screen successive downward movements in a direction transverse to its plane, spring means for sustaining said screen and moving it upwardly, and means for varying the direction or distribution of pressure of said spring in relation to the normal plane of the screen to compensate for the tendency of said screen to tip under different loads, substantially as described.

In testimony whereof, I affix my signature in presence of two witnesses.

RANDALL P. AKINS.
